Incorporated, New York, N.Y., a corporation of
New York

Filed Mar. 10, 1960, Ser. No. 14,027
5 Claims. (Cl. 209—75)

This invention relates to verification and sorting machines and more particularly to an automatic machine for determining whether articles being indexed therethrough conform to pre-established coded specifications.

The prime object of this invention is to provide a new and improved automatic article-verification machine.

Testing the various characteristics of articles such as relay contact combs has, in the past, required a plurality of separate and distinct manual and/or mechanized operations which is both time consuming and costly. To achieve rapid verification of a run of articles, it is highly desirable to provide an automatic machine with means for determining whether the articles being successively subjected to various testing operations conform to pre-established coded specifications. Furthermore, it is desirable that a machine include functionally independent testing stations which can be individually coded to perform a series of tests on articles being successively advanced relative thereto.

Therefore, an additional object of the invention is to provide a verification machine having a plurality of independent test stations which function to perform a sequence of tests on articles being successively indexed therethrough.

A further object of this invention is to provide a verification machine having a drive means for actuating a plurality of testing devices in timed relation to an indexing means which advances the articles into alignment therewith.

Another object of this invention resides in providing an automatic verification machine with a control means that is responsive to a coded medium for selectively establishing the conditions for each test to be performed on articles being indexed therethrough.

A more finite object of the invention resides in the provision of a verification machine having a sensing means associated with each of the test stations for ascertaining whether an article is properly aligned therewith prior to the performance of a test thereon.

It is a further object of the invention to provide an improved machine for sorting articles in accordance with a selected characteristic thereof, wherein means for detecting a selected characteristic of the articles are adjusted by a coded control medium to determine the article characteristic to be detected.

With these and other objects in view, the present invention contemplates an automatic verification machine, a preferred embodiment of which includes a plurality of test stations that are rendered effective to ascertain whether articles being successively indexed relative thereto conform to pre-established coded specifications. The tests performed on articles aligned with the various testing stations are conducted simultaneously and involve the actuation of pivotally mounted test heads that move into engagement with the articles subsequent to their having been indexed into alignment therewith. A main drive shaft having a plurality of cams mounted thereon not only effects the simultaneous operation of the various test heads but also controls the actuation of an indexing means which functions to advance the articles relative to the test heads in timed relation to the testing operations performed thereby. A discharge device is pro-

vided at each of the various test stations and is rendered effective subsequent to the determination that an article under test does not conform to the specifications dictated by the coded medium.

5 Other objects and advantages of the present invention will become apparent from the following description of a specific embodiment thereof when considered in conjunction with the accompanying drawings wherein:

FIG. 1 is a front elevational view partially broken away of an automatic article-verification machine embodying the principles of the present invention;

FIG. 1A is a partial horizontal sectional view taken along the line 1A—1A of FIG. 1 illustrating an indexing control means;

10 FIG. 2 is a plan view of the verification machine illustrated in FIG. 1, which depicts the relative positions of the various test stations;

FIG. 3 is an enlarged fragmentary elevation illustrating a card feed mechanism which conditions a control circuit associated with the verification machine for operation;

15 FIG. 4 is an enlarged side elevation partially in section taken along the line 4—4 of FIG. 3 further illustrating the card feed mechanism shown in FIG. 3;

FIG. 5 is an enlarged horizontal cross-sectional view taken along the line 5—5 of FIG. 3 illustrating the cooperation of a punched card with the control switches;

20 FIG. 6 is an enlarged perspective view of a relay contact comb which is subjected to the various tests performed by the automatic verification machine;

FIG. 6A is an end view of a portion of relay contact combs illustrated in FIG. 6;

25 FIG. 7 is a fragmentary plan view illustrating a 500 volt breakdown test head in a retracted position with an article positioned in alignment therewith;

FIG. 8 is a fragmentary vertical cross-sectional view taken along the line 8—8 of FIG. 7 depicting a discharge device of the type provided at each of the various test stations of the verification machine;

30 FIG. 9 is an enlarged fragmentary side view taken along the line 9—9 of FIG. 7 again illustrating the 500 volt breakdown test head in an unactuated position;

FIG. 9A is an enlarged fragmentary sectional view illustrating a pivotally mounted cam-operated actuating means for the 500 volt test head;

FIG. 10 is a vertical cross-sectional view taken along the line 10—10 of FIG. 7 illustrating a conveyor for removing articles to a pair of reject magazines subsequent to the actuation of the escapement device;

FIG. 11 is a fragmentary plan view of the conveyor illustrated in FIG. 10;

FIG. 12 is a fragmentary vertical cross-sectional view taken along the line 12—12 of FIG. 2 illustrating the magazines whereto rejected articles are advanced by the conveyor illustrated in FIGS. 10 and 11;

55 FIG. 13 is a fragmentary view of the upper portion of one of the reject magazines illustrated in FIG. 12;

FIG. 14 is an enlarged fragmentary plan view of a removal device that is utilized to feed rejected articles to the magazines;

60 FIG. 15 is a vertical cross-sectional view taken along the line 15—15 of FIG. 14 illustrating a gate device which functions to align articles with one of the two reject magazines provided at each test station;

FIG. 16 is a fragmentary cross-sectional view taken along the line 16—16 of FIG. 14;

FIG. 17 is an enlarged vertical cross-sectional view taken along the line 17—17 of FIG. 2 depicting a guide fin detector test head in a retracted position;

70 FIG. 17A is an enlarged fragmentary sectional view illustrating a pivotally mounted cam operated actuating means for the guide fin detector test head;

FIG. 18 is an enlarged fragmentary plan view of the guide fin detector test head with an article positioned in alignment therewith;

FIG. 19 illustrates the guide fin detector test head in an actuated position;

FIG. 20 is an enlarged vertical cross-sectional view taken along the line 20—20 of FIG. 19 illustrating a plurality of sensing fingers of the guide fin detector test head and sensing switches actuated thereby;

FIG. 21 is an enlarged vertical cross-sectional view taken along the line 21—21 of FIG. 2 depicting a contact metal detector test head in a retracted position;

FIG. 21A is an enlarged fragmentary sectional view illustrating a pivotally mounted cam operated actuating means for the contact metal detector test head;

FIG. 22 is an enlarged fragmentary plan view of the contact metal detector test head illustrated in FIG. 21;

FIG. 23 is an enlarged fragmentary view of an article turnover device and an actuating means therefor;

FIG. 24 is an enlarged vertical cross-sectional view taken along the line 24—24 of FIG. 23 depicting the turnover device with an article positioned therein;

FIG. 25 is a vertical cross-sectional view taken along the line 25—25 of FIG. 24 illustrating the turnover device and a portion of the indexing means that cooperates therewith;

FIG. 26 is a linear timing chart illustrating the relative actuating times of the article turnover cam, the article transfer cam and the article test fixture cams; and

FIGS. 27-33 illustrate a simplified schematic diagram of an electrical control circuit for the verification machine depicted in the other figures.

Referring to the drawings and more particularly to FIGS. 1, 2 and 6, the manner in which the illustrated embodiment of the automatic verification machine functions and the operations performed thereby will be broadly outlined. A supply of relay contact combs generally designated by the numeral 50 (FIG. 6) is selectively fed to the verification machine from an article-feeding magazine (not shown) similar to that disclosed in the patent to E. W. Larsen et al., Patent No. 2,846,832. The relay contact combs, which are assembled in wire spring relays after the testing thereof, comprise a row of elongated wires 51 that are molded in spaced relation to each other within two blocks 52A and 52B of an insulating material such as molded phenolic plastic.

The specific use to which each of the combs is to be put requires that the structural features thereof conform to pre-established specifications. Accordingly, it may be desired that one, several or all of the wires 51 have precious metal contacts 53_b and 53_m deposited on contact blocks or base elements 54 that are secured to one extremity thereof.

When the combs are assembled in wire spring relays, one group of precious metal contacts 53_b, deposited on the lower side of each comb 50, will normally be engaged by a lower group of terminal contactors 56, as seen in FIG. 6A. Those precious metal contacts 53_m deposited on the upper side of each comb normally will be disengaged from associated upper terminal contactors aligned therewith. Upon energization of the assembled wire spring relay, successive switching operations result in the contact 53_b being disengaged from associated contactors 56 and the contacts 53_m being engaged by associated contacts. To enhance the clarity of the following description and since the wire spring relays in which the combs are utilized are characterized by this Make-Break action of the contactors 56, the upper side of the comb whereon the contacts 53_m are provided will be hereinafter referred to as the make side and the lower portion of the comb will be designated as the break side.

The block 52B is constructed to provide a plurality of guide fins 57 that function to separate the terminal contactors 56 and preclude the possibility of shorting therebetween subsequent to the assemblage of a relay. It is

necessary, therefore, when verifying the characteristics of a run of relay contact combs, to determine whether precious metal contacts have been deposited on the designated base elements and whether a guide fin is formed on the insulating block 52B adjacent each of the contacts.

Referring to FIGS. 1 and 2, there is shown a group of five stations whereat testing operations are performed on the relay contact combs as they are indexed through the verification machine. At the first test station generally designated by the numeral 61, a 500 volt potential is applied to adjacent wires of a comb 50 aligned therewith to test the breakdown characteristics of the insulating blocks 52A and 52B.

A second station generally designated by the numeral 62 tests for the presence or absence of plastic guide fins 57 adjacent to those wires 51 having precious metal contacts deposited on the associated base element 54. Subsequent thereto, the relay contact combs are indexed to a third station generally designated by the numeral 63 at which a test is performed to determine whether precious metal contacts are present where required.

The tests performed on the relay contact combs at stations 62 and 63 check only the characteristics of the upper or make side of the combs. Accordingly, it is necessary to rotate the combs 180 degrees in order that the bottom or break side of each can be subjected to contact detecting and fin sensing tests. The rotation of the combs is accomplished at the station generally designated by the numeral 64 and, as is the case with the operation of the other testing station, is performed in timed relationship to the actuation of the indexing means.

The test stations generally designated by the numerals 66 and 67 perform contact metal detector and fin sensing tests, respectively, on the break side of the relay contact combs. A comb which has satisfactorily passed each of the tests at the various stations is thereafter indexed to a discharge station (not shown). Should a relay contact comb fail to conform to the coded specifications for which the various test stations have been conditioned, a discharge device associated with the station at which the article is determined to be defective is rendered operable and the rejected article is shunted to one of two reject magazines generally designated by the numerals 68 and 69.

As previously described, it is essential to condition each of the test stations for the particular characteristics of the combs to be tested. Accordingly, a punched card generally designated by the numeral 71 (FIG. 5) is utilized to present coded information to a control circuit to be hereinafter described. One edge of the card 71 has cutaway portion 71_a corresponding to and indicative of the condition wherein no precious metal contact is required and residual portions 71_b corresponding to and indicative of the condition wherein a precious metal contact is required. Two such edge portions are provided for each contact block, one for the upper side and the other for the lower side.

The card 71 illustrated in FIG. 5 represents the manner in which a card is punched so that the verification machine is conditioned to accept articles having the characteristics of the comb illustrated in FIG. 6. It will be noted in viewing this comb that the first wire 51 of the first group of four wires projecting from the body 52B has no base element 54 associated therewith. In keeping with absence of precious metal contacts on the first wire, two cutouts are present in the card 71 in the left-hand extremity thereof. The second wire 51 has a precious metal contact 53_b deposited on the bottom or break side of the contact block 54 but none on the upper or make side. Therefore, only one cutout is present in that portion of the card 71 representing this second wire. Since contacts are present on both the make and break side of the base element 54 secured to the third wire, no cutouts or punches are present in that portion of the card 71 relating thereto. A contact 53_m is present on

the upper side of the contact block secured to the fourth wire projecting from the block 52B; accordingly, one cut-out is provided in that portion of the card. Since the characteristics of the second group of four wires are identical to those of the first group, the second half of the card will be punched in a manner identical to the first half thereof.

It is intended that each of the combs tested have characteristics which conform to the information punched in the card 71 and that the absence of any of the precious metal contacts required or the absence of a guide fin adjacent thereto will result in an article being rejected. It is further intended that the breakdown of the insulating material between adjacent wires will also cause an article to be rejected. If a precious metal contact is present on a base element where not required, the article may nevertheless pass the various tests performed by the machine. Although the article won't conform to the coded specifications, the presence of an additional precious metal contact will not result in a malfunction of the particular relays wherein the combs are used.

GENERAL STRUCTURAL FEATURES

The verification machine comprises a base or cabinet structure 77 (FIG. 1) having a lower support plate 78 whereon a drive motor 79 is securely mounted. The motor 79 drives a speed reducer 81 which transmits motion through a belt and pulley apparatus generally designated by the numeral 82 to a main drive shaft 83. The drive shaft 83 is supported within a plurality of bushing members 84 that extend from an upper support plate 86 of the cabinet structure 77.

The main drive shaft 83 has secured thereto a plurality of cams (FIGS. 1A, 9A, 17A and 21A) which effect the actuation of the various test heads and an article indexing means. Also secured to the shaft 83 is a belt and pulley apparatus 87 which serves to drive a conveyor means associated with a discharge device that is provided at each of the test stations. Mounted above and toward the rearward portion of the upper support plate 86 is a control panel generally designated by the numeral 90 wherein a card feed mechanism 76 is located.

Card feed mechanism

The card feed mechanism 76 (FIGS. 3, 4 and 5) includes a housing 91 having a pair of end plates 92 and 93 between which is secured a pair of L-shaped support brackets 94. A shaft 96 is pivotally mounted within and extends beyond the end plates 92 and 93. Secured to the shaft 96 is a card holder 97 having a bed plate 98 on which the punched card 71 is placed.

A pair of roller arms 101 and 102 are pivotally mounted on the end plates 92 and 93 respectively. One extremity of each of the roller arms is urged in an outward direction from a backing plate 103 by a spring-biased arm 104. The other extremity of each of the roller arms 101 and 102 has rotatably secured thereto a roller 106. The rollers 106 function to engage detents 107 formed in a pair of side plates 108 of the holder 97 and maintain the holder in the dotted position shown in FIG. 4 as an aid to the rapid insertion and removal of the punched card.

Subsequent to the positioning of the card 71 within the holder 97, the holder is manually pivoted in a clockwise direction as viewed in FIG. 4 until the leading edge of the card selectively actuates switch arms 109 which are associated with a plurality of normally open switches. Two switches are provided for each wire 51, one for each possible precious metal contact 53_m—53_b, and an additional switch is employed as a card sensor. The eight switches associated with the upper contacts 53_m are mounted on the upper of the two brackets 94 and are designated M1—M8, and the eight switches associated with the lower contacts 53_b are mounted on the lower of the two brackets 94 and are designated B1—B8.

The card sensing switch is mounted alongside the switch M8 on the upper bracket and is designated by the letter S.

Switches M1 and B1 condition a verification circuit for the make and break sides of the first wire 51. Similarly M2 and B2 condition a verification circuit for the second wire and so on for the eight wires mounted within the blocks 52A and 52B. In the illustrated example, the first and fifth wires of the comb 50 do not need to be checked for precious metal contacts 53 or guide fins 57 on either the make or break sides thereof. Accordingly, the card 71 is punched to preclude switches M1, B1, M5 and B5 from being actuated.

A precious metal contact should be provided on the break side of the contact block secured to the second wire 15 of both the first and second groups. Accordingly, the card 71 has residual portions to actuate switches B2 and B6 and punched or cutaway portions corresponding to switches M2 and M6. Manifestly, to condition the test circuits for the remaining precious metal contacts of the 20 comb 50 as illustrated in FIG. 6, switches M3, B3, M4, M7, B7 and B8 should be actuated by residual edge portions of the card 71 while the arms 109 of switches B8 and B4 will move into the cutout edge portions of the card and will not be actuated when the card holder 97 is 25 pivoted within the housing 91.

Indexing mechanism

Successive relay contact combs are advanced step by step through the verification machine by the drive motor 30 79 acting through indexing or reciprocating transfer means 35 illustrated in FIGS. 1, 1A and 25. This transfer means includes a drum cam 111 and a cam follower 112 received within a cam groove 113 as shown.

The cam follower 112 is carried by an arm 112_a which is pivotally mounted on a fixed, vertical shaft 114. As the cam follower 112 traces the cam groove 113, the arm 112_a is caused to oscillate about the shaft 114. This oscillatory movement is transmitted through a link 117 (FIG. 1A) to a pair of arms 118, the link 117 being connected 40 to the cam follower 112 by a pin 116. The arms 118 are secured to sleeves 120 rotatable about fixed rods or shafts 119.

The shafts 119 and associated sleeves 120 extend upwardly through the support plate 86, and secured to the upper extremities of the sleeves are a pair of arms 121, best seen in FIG. 2. These linking arms are drivingly connected to a transfer rack 123 through pin or roller and slot connections generally designated 122. The rack 123 is supported by a fixed bar 127 through rollers 126 which are rotatably mounted on the bar 127 and are received within slots 123_a in the rack 123, suitable guides (not shown in the drawings) being provided for holding the rack against the bar 127. The bar 127, in addition to supporting the rack 123, serves as a guide member for the relay combs 50, it being arranged immediately above 55 a bed or transfer plate 125 along which the combs are moved.

It will now be apparent that as the arms 118 and 121 are caused to oscillate by the motor 79 and the drum cam 111, the rack 123 will be made to reciprocate longitudinally of itself. A plurality of pawls or indexing fingers 124 pivotally mounted on the rack 123 engage the relay combs 50 as best seen in FIG. 25 and cause intermittent, unilateral movement of the combs in response to reciprocatory movement of the rack 123. More particularly, as the transfer rack 123 moves from right to left as viewed in FIG. 25, the indexing fingers 124 will be pivoted in a counterclockwise direction and freely pass over the articles 50. As the rearward motion of the rack 123 is completed, each finger 124 will pivot down into position to engage an article. The return motion from left to right will result in the article being forced ahead by the finger to the next succeeding position.

Dielectric breakdown test station

75 The dielectric test station 61, best seen in FIGS. 7, 9

and 9A, includes a 500 volt test head generally designated by the numeral 131. The test head 131 is secured to the upper end of an arm 134 which is pivotally mounted on a fixed bracket 132 by a pin 136. The arm 134 is caused to pivot about the pin 136 by a cam 135, secured to the drive shaft 83, acting through a cam follower 136 and interconnecting linkage. More particularly, the cam follower 136 is mounted on an arm 137 which is pivotable about a pin 138, the arm being urged in a clockwise direction by a spring 139 such that the cam follower 136 is made to bear against the cam 135. The upper end of the arm 137 is linked with the test head arm 134 by a link 140 such that pivotal movement of the arm 137 induced by the cam 135 and the spring 139 is transferred to the test head arm.

The test fixture 131 is provided with a plurality of horizontally aligned female receptacles 146, four of which have a 500 volt breakdown potential selectively supplied thereto by a plurality of conductors 147. The receptacles 146 (FIGS. 7 and 9) are mounted in two groups of four each within the test fixture 131 and complement the arrangement of the wires 51 projecting from an article 50 aligned therewith. Rotation of the cam 135 and resultant rocking of the test head toward the relay comb 50 causes reception of the ends of wires 51 within the receptacles 146 of the test fixtures 131. This rocking of the test fixture is performed in timed relation to the advance of the articles 50 relative to the test station 61. Immediately after an article has been advanced into alignment with the test head 131, the receptacles 146 engage the wires 51. Thereafter, a 500 volt breakdown potential is applied to alternate wires to ascertain whether the dielectric characteristics of the phenolic blocks 52A and 52B conform to pre-established requirements. Subsequent to a completion of the breakdown test, the test head is pivoted to its retracted position (shown in FIGS. 7 and 9) and the tested article is advanced to the next succeeding position.

Guide fin verification station

The guide fin verification tests performed at stations 62 and 67 are accomplished by a test head 161 which is illustrated in FIGS. 17, 17A, 18, 19 and 20. The test head includes a frame 165 which is pivotally mounted on a shaft 166. A plurality of sensing fingers 168 are pivotally mounted on a rod 169 secured to the frame 165 and are urged into contact with the frame by spring members 171. A plurality of small normally open switches 172 are arranged on the frame 165, one above each finger 168, in position to be operated by upward movement of the corresponding finger. As is described in greater detail below, it is intended that the frame 165 be rocked about the shaft 166 to bring the fingers 168 against the fins 57 of the comb 50, the switches 172 corresponding to the fingers 168 which sense fins being actuated by this operation.

Prior to such sensing of comb fins, a pin 173 that is secured to the test head checks for proper comb alignment and to a limited extent corrects misalignment. The pin 173 projects downwardly from the forwardmost extremity of a yoke 167 which is pivoted on the shaft 166. A spring 174 urges the yoke 167 in a counterclockwise direction with respect to the frame 165, relative motion in this direction being limited by an adjustable screw 167a. The pin 173 is so positioned that downward pivotal movement of the test head moves the pin into the space between the two groups of elongated wires 51 of a properly aligned comb 50. Should an article not be properly aligned with the test head 161, the pin 173 will engage a portion thereof, thereby precluding the yoke 167 from moving with the frame 165. Manifestly, the frame 167 will pivot about the shaft 166 against the action of the spring 174. The continued advance of the frame 165 to a test position will result in the actuating member 177 of a normally closed limit switch 176 being engaged by a bolt 178 which is adjustably secured within the frame

167. The switch 176 is included in the control circuit for the drive motor 79 and, upon being actuated, will preclude the further operation thereof.

When an article is in proper alignment at the test station, the pivoting of the test head 161 will advance the pin 173 between the two groups of wires 51 and the fins 57 will be engaged by and cause the fingers 168 to pivot about the rod 169. Each of the fingers 168 will, thereupon, move into engagement with the switch 172 aligned therewith, resulting in the actuation thereof. The contacts associated with the switches 172 are included in a portion of the control circuit to be hereinafter described and function to indicate the presence or absence of guide fins 57 on the block 52B.

15 The pivoting of the test head subsequent to the alignment of a comb therewith by the indexing apparatus is effected by a radial cam 163 that is keyed to the main drive shaft 83 (see FIG. 17A). An arm 162 is pivotally mounted on a fixed bracket 170 by a pin 164 and is maintained in positive engagement with the cam 163 by a spring 160. The upper, bifurcated extremity of the arm 162 receives a roller 175 which is carried by the pivotally mounted frame 165 of the test head 161. Pivotal movement of the arm 162 which is induced by the cam 25 163 and the spring 160 is imparted to the frame 165 and results in the pivoting thereof about the shaft 166.

Contact metal detector test head

As illustrated in FIGS. 21, 21A and 22, a contact metal detector test head 181 of the type provided at test stations 63 and 66 includes a support frame 194 that has a plurality of sensing fingers 195 mounted thereon. The support frame 194 is pivotally mounted on a shaft 196 that is mounted within a pair of brackets 197 extending upwardly from the support plate 86. The fingers 195 are mounted on the frame 194 in spaced relationship and are positioned so that upon pivoting of the frame, the fingers will be brought into engagement with contact blocks of the comb aligned with the test head.

40 An L-shaped positioning arm designated by the numeral 198 is mounted on the shaft 196 for movement normally with the support frame 194, but may be pivoted in a clockwise direction, relative to the support frame against the action of a spring 199. The function of the L-shaped positioning arm 198 is to sense proper comb alignment and to correct minor misalignment prior to a testing operation. If an article 50 is sufficiently misaligned, the arm 198 is not able to pass between the two groups of elongated wires 51 that extend between the blocks 52A and 52B. Accordingly, as the test head 45 181 is rotated further toward a misaligned comb, the frame 194 is moved relative to the restrained positioning arm and will withdraw an actuating arm 201a of a switch 201 from engagement with a downwardly projecting member 202 of the arm 198. The switch 201 functions in a manner analogous to the switch 176 associated with the guide fin test head, and, upon being disengaged, will cause the operation of the drive motor 79 to be interrupted.

50 When a comb 50 is properly aligned with the test head 181, the pivoting of the support frame 194 in timed relation to the indexing means will bring the sensing fingers 195 into engagement with the one surface of the contact blocks 54 secured to the extremities of the elongated wires 51. One sensing finger 195 is provided for each wire projecting from the block 52. The sensing fingers 195 are heated to and maintained at a temperature of approximately 250° F. by heaters 207 which are secured to the frame 194. The coalescence of a heated finger 195 and a precious metal contact such as palladium will result in the generation of a thermal E.M.F. The magnitude and polarity of the generated E.M.F. is sensed by an acceptance circuit (FIG. 32) which is pre-conditioned to specified requirements of the run of combs. 55 The method and apparatus utilized to ascertain the pres-

ence or absence of precious metal contacts by sensing the magnitude and polarity of a generated thermal E.M.F. is disclosed and claimed in the commonly assigned co-pending application of M. J. Brown-G. W. Humphreys, Serial No. 14,020, filed March 10, 1960.

The selective pivoting of the test head 181 (FIG. 21) and the advance of the heated fingers 195 into engagement with one surface of the contact blocks 54 is effected by a cam 183 that is secured to the main drive shaft 83 by a key 184. A roller 193, that is secured to the pivotally mounted support frame 194, is positioned in a bifurcated end portion 187_a of an arm 187 that is pivotally secured to a fixed bracket 191 by a pin 192. A cam follower 186 is mounted on the arm 187 and is maintained in positive engagement with the cam by a spring 188. The cam 183 is provided with a second cam surface 208 which engages a cam follower 209 that is secured to a pivotally mounted linking arm 211. This linking arm 211 is secured by a bar 210 to a fixture support member 212 whereon a plurality of female receptacles 213 are mounted within a block of insulating material 214.

Rotation of the cam 183 causes the concomitant pivoting of the support member 212 and the arm 187. The arm 187 imparts pivotal movement to the support frame 194 thereby bringing the heated fingers 195 into engagement with one side of the contact blocks of the comb under test. At the same time, the support member 212 advances the female receptacles 213 into engagement with the wires 51 to complete the acceptance test circuit.

Article turnover station

Guide fin and contact metal detector tests are performed on both the upper (make) and lower (break) sides of the contact relay combs 50. Therefore, it is necessary to rotate the combs subsequent to the performance of tests on one side thereof. The rotation of the contact relay combs 50 is accomplished in timed relation to the indexing of the combs at the turnover station 64 and will best be understood by reference to FIGS. 23, 24 and 25.

A barrel cam 221 that has a groove 225 formed therein is mounted on the main drive shaft 83 adjacent the barrel cam 111 previously referred to. An arm 222, which is pivotally secured to the support frame 77 by a pin 223, has secured thereto a cam follower 224 that is received within the groove 225 of the cam 221. The upper extremity 227 of the arm 222 is bifurcated to receive a pin 228 that projects from a rack 229.

The rack 229 is slidably mounted on a frame 230, the rack having a portion 229' which dovetails with a portion 230' of the frame 230. This frame 230 is secured to the upper support plate 86 and the rack is caused to slide relative thereto upon reciprocation of the linking arm 222. A pinion gear 232 is positioned in alignment with the rack 229 and is rotated in oscillatory fashion thereby as the rack moves back and forth during the rotation of the barrel cam 221. More particularly, as the cam follower 224 traces the groove 225, the arm 222 is pivoted about the pin 223 and imparts bilateral motion to the rack 229.

A one-way clutch 234, which may be of conventional construction, is mounted adjacent the gear 232 on a shaft 237 that projects outwardly from one extremity of a turnover housing generally designated by the numeral 236, the clutch functioning to preclude any counterclockwise rotation of the housing as seen in FIG. 25. It should be noted that the gear 232 is freely rotatable on the shaft 237. A pin 239 projects from the rearward extremity of the housing 236 (FIG. 24) and is rotatably mounted within a support member 241 that extends upwardly from the support plate 86. The structural features of the above-described turnover device are similar to those of the article turnover device disclosed and claimed in the patent to C. R. Rasmussen, Patent No. 2,881,899, filed January 28, 1957.

When an article is advanced to and within the turnover housing 236 by an indexing finger 124, the timed reciprocation of the linking arm 222 effects a clockwise rotation of the housing through 180° (FIG. 25), thereby turning over a comb which is positioned on a support bracket 238 within the housing. A spring urged detent member 242 which is positioned within the frame 230 moves into a groove 243 formed in the outer periphery of the housing 236 when the groove is rotated into alignment therewith and insures that the housing stops in the proper angular orientation. Subsequent to the rotation of the housing, a hook-like member 246 that is secured to the rack 123 is advanced into the apertured portion of the housing and is cammed over the comb 50 therein. During the return stroke of the rack, this member engages and removes the rotated article from the housing while another article is advanced thereinto in anticipation of a subsequent turnover operation.

Discharge device and reject magazine

As previously set forth, a discharge device is provided at each of the stations wherat tests are performed on the contact relay combs. Accordingly, an independently operable discharge device is associated with the dielectric breakdown test head and with each of the guide fin verification test heads and contact metal detector test heads. The selective actuation of the discharge devices to reject defective combs at each of these test stations is effected by a plurality of solenoids which are included in the control circuit to be hereinafter described.

The transfer plate 125 over which the contact relay combs are successively indexed has a trap door 252 provided therein in alignment with each of the best heads as is best seen in FIG. 8. A piston arm 253 of an air cylinder 254, which is controlled by the solenoids previously referred to, is secured to the trap door 252 by means of a linking arm 255. Upon ascertaining a defective article, the cylinder 254 is rendered operative and causes the piston arm 253 to be retracted. Retraction of the arm 253 pivots the trap door 252 about a pin 257 and into engagement with a switch 260. A defective article positioned on the trap door 252 is dropped onto a deflector plate 258 and transferred to a conveyor generally designated by the numeral 259 (FIGS. 10 and 11). The conveyor 259 is of the endless belt type and includes a belt 261, idler pulleys 264 and a pulley 262 secured to a drive shaft 263. The shaft 263 and, accordingly the belt 261 are driven by the belt and pulley apparatus 87 and advance the rejected articles to a second conveyor 266.

Referring now to FIGS. 12-16, the manner in which the rejected combs are selectively shunted to the magazines 68 and 69 from the conveyor 266 will be set forth. Rejected combs are transferred by the conveyor 266 until brought into engagement with a gate 272 and thereby precluded from further advancement. The gate 272 is positioned so that an article advanced into engagement therewith will be aligned with the reject magazine 69. A shaft 273, which is rotatably mounted within bushing members (not shown) directly above and in alignment with the conveyor 266, has mounted thereon an arm 274 that rotates therewith. Secured to the lower extremity of the arm 274 is a tubular member 275 positioned to sweep across the conveyor 266 immediately thereabove and drive any comb engaging the gate 272 off the conveyor across a transfer plate 277 and into the reject magazine 69. The reject magazines 68 and 69 are provided with a slot 278 to receive the rejected combs in uniform fashion.

As previously indicated, two reject magazines 68 and 69 are provided adjacent each test station. The gate 272 serves to direct rejected combs into the first magazine 69 until it is filled, after which the gate 272, under the control of apparatus described immediately below, permits combs to be directed to the second magazine 68. This arrangement permits emptying of the reject magazines without interrupting normal operation of the machine.

The apparatus for effecting automatic actuation of the gate 272 includes a pair of light sources 281 and 282 arranged on the inner surface of each magazine and projecting light across an apertured portion thereof to a pair of photoelectric cells 283 and 284 that are mounted within the frame of the magazine. It is intended that filling of the magazine with rejected combs will interrupt the light beams, deenergize the photoelectric cells and produce a warning signal through actuation of a solenoid 286 (see FIG. 15). The circuitry through which the photoelectric cells control the solenoid 286 is described below along with other control circuits.

An actuating arm 287 of the solenoid 286 is secured to a pivotally mounted arm 288. One extremity of this arm is secured by a pin 289 to the lower portion of a shaft 291 to which the gate 272 is secured. Interposed between the lower extremity of the shaft 291 and a support bracket 292, on which the solenoid 286 is mounted, is a spring 293 that normally functions to maintain the gate in a closed (down) position. Upon actuation of the solenoid 286, the force of the spring 293 is overcome and the gate is raised so that subsequently rejected combs will be advanced under and past the gate and into alignment with the second reject magazine 68. Apparatus which may be identical to that described above is provided for driving combs off the conveyor 266 and into the magazine 68.

Each of the reject magazines 68 and 69 is pivotally mounted on a rod 301 that is secured within the lower portion of the support frame. When the first magazine has been filled and the gate has been raised, an operator in attendance may thereafter grasp a handle 302 and pivot the magazine to an open position to facilitate the removal of defective articles therefrom.

Mode of operation

To facilitate an understanding of the automatic operation of the machine and to eliminate the need for duplicating the showing and explanation of identical circuits that are associated with more than one test station, the various circuits provided for the verification machine illustrated in FIGS. 27-33 have been separated into distinct units.

A motor starting and control circuit is illustrated in FIG. 27 and is conditioned for operation in accordance with information derived from the punched card and fed to a master control relay circuit that is illustrated in FIG. 28. FIG. 29 represents an acceptance circuit associated with the 500 volt dielectric test station 61. A circuit such as that illustrated in FIG. 30 is provided for each of the test stations 62 and 67 wherein guide fin verification tests are performed, and an acceptance circuit of the type illustrated in FIG. 31 is provided for each of the test stations 62, 63, 66 and 67.

The various circuits are provided with a plurality of relays, the contacts of which may or may not be included in that same circuit. In order to facilitate association of relays and relay contacts without detailed explanation thereof, relay contacts operated by a relay are designated herein by the relay reference numeral followed by an identifying subscript letter. For example, the contacts controlled by a relay 402 are designated 402_a, 402_b and 402_c, etc. Safety switches, limit switches, push-button switches and the like are readily distinguishable from relay contacts since each of these various switches is designated by a whole number only.

At the outset of a cycle of operation, a normally open push button On switch 401 is depressed to complete a path for energizing current to a relay 402. Energizing current for the relay 402 is tapped from two conductors 404 and 406 of a three-phase system for the control motor 79 through a normally closed push button Off switch 400. Power is supplied to the conductors 404 and 406 and a conductor 405 from a source thereof upon closure of a master control switch 408.

When energized, relay 402 closes normally open contacts 402_a and 402_b, and locking contact 402_c. Contacts 402_a and 402_b supply potential to conductors 409 and 411 through a transformer generally designated by the numeral 412. Energizing potential supplied to the conductors 409 and 411 is applied to a 120 second timer 413 through a normally closed contact 414_a of a relay 414. The purpose of the timer 413 is to insure that the filaments of the various components included in the control circuit have sufficient time to warm up prior to the utilization thereof.

Subsequent to the expiration of the two-minute timing period and the energization of the timer 413, closure of a contact 413_a associated therewith completes a path for energizing current to the relay 414, resulting in the opening of the energizing circuit to the timer 413 by a contact 414_a and the closure of contacts 414_b and 414_c.

The contact 414_b is included in the energizing circuit for a drive motor control relay 416. Included in series with the contact 414_b is a contact 176_m of the switch 176 that is provided at the first guide fin verification station 62, a contact 176_b associated with the switch 176 at the second guide fin verification station 67 and a pair of contacts 201_m and 201_b that are controlled by the actuation of the switches 201 at the first and second contact metal detector test stations 63 and 66. It will be recalled that these switches are actuated only when a test head is brought into engagement with a misaligned relay contact comb.

Also included in series with the contact 414_b is a contact 441_a. The contact 441_a is closed upon energization 30 of a relay 441 (FIG. 28) subsequent to the actuation of the card detecting switch S resulting from the insertion of a punched card into the machine. A pair of contacts 419_a and 420_a that are controlled by thermostatically controlled relays 419 and 420, respectively (explained below) and five normally closed relay contacts 426_a are also included in the energizing circuit for the relay 416. The relay contacts 426_a are opened when control relays 426, which are associated with the second stage of each of the reject magazine control circuits (FIG. 33) provided at 40 test stations 61, 62, 63, 66 and 67, are deenergized. Accordingly, these contacts will only be opened when both of the reject magazines 68 and 69 are filled with defective articles. Also included is a normally closed push button Stop switch 432 provided for manual stopping of the motor 79. A normally open push button Start switch 433 connects the Stop switch 432 to the motor control relay 416, a two-position Off-Run switch 434 and a locking contact 416_d that is closed upon energization of the relay 416 being arranged in parallel with the Start switch 433.

50 A cycle of operation of the automatic verification machine is commenced when the Start switch 433 and Off-Run switch 434 are closed subsequent to the insertion of a punched card 71 into the machine and the resulting energization of the relay 441 which closes the contact 441_a. Assuming the switch 501 has previously been closed and that the two-minute timing period has elapsed, the contact 414_b will also be closed.

The energizing circuit for the motor control relay 416 is completed by the contacts 419_a and 420_a that are drawn up upon energization of the relays 419 and 420. 60 The energization of relays 419 and 420 occurs subsequent to the drawing up of a pair of thermostat contacts 443 and 444 which occurs prior to the expiration of the two-minute timing period when the heaters 207 reach a pre-established temperature. The temperature attained by the heaters 207 for the two contact metal detector test heads is controlled by normally closed contacts 446 and 447 of a second pair of thermostats 448 and 449.

70 Contacts 416_a, 416_b and 416_c, which are closed upon energization of the drive motor control relay 416, apply three-phase potential which is supplied by the conductors 404, 405 and 406 to the motor 79. Upon being rendered effective, the motor 79 will impart rotary motion to the drive shaft 83 and the indexing of combs in timed relation to the testing thereof will be commenced. Subse-

quent to the actuation of the drive motor 79, relay contact combs 50 are advanced by the indexing means into alignment with each of the various test heads. As previously set forth, the verification machine simultaneously performs tests on five articles aligned with each test head; while at the turnover station 64, an article is rotated 180°.

At the first test station 61, the 500 volt test head is brought into engagement with adjacent wires of the comb 50 aligned therewith and applies a 500 volt breakdown potential to alternate ones of the wires. The acceptance circuit for the dielectric test performed at station 61 is illustrated in FIG. 29 and is supplied with energizing potential by the conductors 409 and 411. This energizing potential is applied to the primary of a transformer 471 through the closed motor control relay contact 416. The potential applied to the primary of the transformer 471 is stepped up at the secondary thereof and applied to alternate wires of the contact comb under test.

If a short exists between adjacent comb wires, a path of energizing current is provided through a relay 472 and a contact 472_a is drawn up. Since a comb which indicates a short between adjacent wires does not conform to pre-established specifications, it is imperative that the article be rejected. A defective comb, however, cannot be dropped through the trap door 252 until the test head 131 is returned to a normal position. A relay 474 that is provided with energizing current subsequent to the closure of the relay contact 472_a provides the necessary time delay between the return of the test head to a normal position and the actuation of the trap door 252. Contacts 474_a and 474_b are closed upon energization of the relay 474, the former locking the relay in an energized state while the latter conditions the discharge device for operation. A third contact 474_c associated with the relay is opened upon the energization thereof and removes breakdown potential from the test head. The cam 143, which effects the pivoting of the test head into and out of testing engagement with the combs 50, also actuates with limit switches 481, 482 and 483. The switch 481 sets up the energizing circuit for the relay 474; while the switches 482 and 483 are utilized within the reject circuit that controls the actuation of the trap door 252.

Subsequent to the return of the test head to a normal position, the cam 143 closes the switch 482, thereby applying energizing potential through a step-down transformer 486 to a Down air solenoid 487. The Down air solenoid 487 actuates the air cylinder 254 which retracts the piston arm 253 and opens the trap door 252. A rejected comb is then shunted to one of the two reject magazines 68 or 69. When the trap door is pivoted a sufficient amount, the actuating arm of the switch 260 of FIG. 8 is engaged, thereby closing the contact 491 of FIG. 29. The closing of contact 491 energizes an Up air solenoid 492 which is conditioned for energization by the closure of the switch 483. The closure of switches 481, 482 and 483 by the cam 143 conditions the acceptance circuit for subsequent test operations each time an article is accepted or rejected and insures that the test head 131 and trap door are in retracted and closed positions respectively.

Referring now to FIG. 28, the manner in which the individual guide fin and contact metal detector test and acceptance circuits are conditioned in accordance with information punched in the card 71 will be set forth. The card 71, which is punched to condition these circuits in accordance with the characteristics of the comb illustrated in FIG. 6, will actuate and close the contacts B2, M3, B3, M4, B6, M7, B7, M8 and S upon the pivoting thereof into engagement with the switches mounted within the card feed mechanism 76.

The closing of contact B2 completes a path for energizing current to a relay 451 that may be traced from the conductor 409 through the contact B2 and the relay 451 to the conductor 411. Similarly, relays 452, 453, 454, 456, 457, 458 and 459 are energized subsequent to the

closure of the switch contacts in series therewith. The remaining relays in the master control relay circuit illustrated in FIG. 28 will not be energized during the testing of combs having the characteristics illustrated in FIG. 6. However, it is conceivable that any number of relays in the master control relay circuit might be energized. It is readily apparent, therefore, that the verification machine may be conditioned to test a run of combs having vastly different characteristics than the run previously tested by merely substituting a new punched card for the one previously used to condition the master control relay circuit.

Four acceptance circuits of the type illustrated in FIG. 31 are provided, one for each of the two guide fin test heads and for each of the two contact metal detector test heads. Inasmuch as the tests performed by the guide fin and contact metal detector test heads at stations 66 and 67 are substantially identical to those performed by the test heads at stations 62 and 63, the following description of a mode of operation thereof will be confined to the circuits associated with the test heads at stations 62 and 63. The test conducted at station 62 is performed on the upper or make side of the relay contact comb. Accordingly, only the control relay contacts 452_a, 454_a, 457_a and 459_a are drawn up to condition four possible reject circuits for energization.

While the 500 volt dielectric strength test is being performed on a relay contact comb positioned at station 61, the guide fin verification test head 161 at station 62 is concomitantly pivoted into testing engagement with an article aligned therewith. The contacts of the switches 172 which are actuated as a result of the engagement of the sensing fingers 168 with guide fingers 57 are included in the test circuit illustrated in FIG. 30. A switch contact 501 is closed when the actuating arm of the first switch 172 is engaged by a sensing finger 168. Similarly, the switch contacts 502—504 and 506—509 are closed when the actuating arms of the remaining seven switches are engaged by the sensing fingers aligned therewith. The closure of the contacts 501—504 and 506—509 energizes relays 511—514 and 516—519 previously conditioned by the cam 163 closing limit switch 521. The energization of relays 511—514 and 516—519 results in the closure of locking contacts 511A—514A and 516A—519A and opening of contacts 511B—514B and 516B—519B. Contacts 511B—514B and 516B—519B, which are included in the acceptance circuit illustrated in FIG. 31, interrupt the several parallel paths for energizing current to a transformer 531 (FIG. 31).

If each of the circuits completed by the closure of the contacts 452_a, 454_a, 457_a and 459_a are interrupted by the opening of contacts 513_b, 514_b, 518_b and 519_b, respectively, energizing current is not provided to the transformer 531. However, should a guide fin 57 be absent from the block 52_b, the switch aligned therewith is not actuated and one of the contacts 511B—514B and 516B—519B is not opened. For example, if the switch contact 503 (FIG. 30) is not closed, the relay 513 cannot be energized and the contact 513_b will not be opened. Accordingly, when the cam 163 closes a limit switch 536, current is provided to the primary of the transformer 531 and a Down air solenoid 532 is energized. The path for current flow which results in the Down air solenoid being energized can be traced from the conductor 409 through the switch 536, the contact 452_a, the contact 513_b and the primary of the transformer 531 to the conductor 411. The closure of limit switches 521 and 536 by the cam 163 in timed relation to the pivoting of the test head 161 insures that the test head is withdrawn prior to the actuation of the air cylinder 254 by the Down air solenoid 532.

In a manner identical to that described for the test station 61, the pivoting of the trap door 252 to discharge a defective comb results in the switch 260 at station No. 2 being engaged and a switch contact 537 associated therewith being closed. The closing of the contact 537

conditions a circuit which includes the switch 538 and the primary of a transformer 539 for energization. The timed actuation of the limit switch 538 results in an Up air solenoid being rendered effective and the return of the trap door 252 to a normal position prior to the advance of the next succeeding comb thereto. During normal operation, however, each of the contacts 511—514 and 516—519 will be opened. Accordingly, energizing current will not be provided to the transformer 531 and the Down air solenoid 532 will be precluded from being rendered effective.

The circuit illustrated in FIG. 32 represents a contact metal detector circuit which is described in detail in the aforementioned copending application of M. J. Brown-G. W. Humphreys. Eight such circuits are provided for each of the test stations 63 and 66 at which the presence or absence of precious metal contacts is verified. These circuits sense the magnitude and polarity of the thermoelectric voltage that is generated when a heated sensing finger 195 engages either a precious metal contact or the upper surface of a contact block 54.

When a precious metal contact is engaged by a heated sensing finger 195, the thermoelectric voltage generated and fed to the input of the detector circuit by a conductor 561 results in a thyratron 562 being rendered conductive. Conduction of the thyratron 562 results in the energization of a relay 563 that is included in the plate circuit thereof. The cam 183 which effects the selective pivoting of the test head 181 into and out of engagement with a comb aligned therewith also controls the timed opening of a limit switch 564 and accordingly, the deenergization of the relay 563.

Each of the detector circuits that has supplied thereto an E.M.F. generated by the coalescence of a heated sensing finger 195 and a precious metal contact has the relay 563 that is included in the plate circuit thereof momentarily energized. The relay contacts associated with the relays 563 of each of the individual detector circuits occupy the same position in the acceptance circuit illustrated in FIG. 31 as the relay contacts 511B—514B and 516B—519B and these contacts will hereinafter be designated by these same numerals. If each of the precious metal contacts is deposited where required, the relay contacts 511B—514B and 516B—519B associated with the energized relays 563 are opened and the Down air solenoid 532 is precluded from energization.

In a manner similar to that previously described for test station No. 2, the absence of one of the necessary precious metal contacts results in the Down air solenoid 532 being actuated and the trap door 252 being pivoted to shunt the defective comb to one of the two reject magazines provided at test station 63. The energization of the Down air solenoid occurs when a heated sensing finger is brought into engagement with a surface of a contact block 54. In this instance, the polarity of the generated E.M.F. is opposite to that of the E.M.F. generated when a precious metal contact is engaged and the thyratron 562 is not rendered conductive. Accordingly, the relay 563 is not energized and a path for current flow is completed to the primary of the transformer 531.

Combs rejected at each of the test stations are fed to the reject magazines of the corresponding test station through the conveyor apparatus previously described. When the gate 272 is down, the defective combs are aligned with and shunted to the reject magazine 69. When the reject magazine 69 is filled, the gate is automatically raised and the defective combs are thereafter fed to the reject magazine 68. The gate 272 at each of the five test stations is normally maintained in a down position as illustrated in FIG. 15 by the solenoid 286 (FIG. 27). Each of the solenoids 286 is conditioned for energization by the closure of relay contacts 414_a, 414_b, 414_f, 414_g and 414_h but remain deenergized until the reject magazine 69 is filled with defective combs.

One of the five control circuits for a gate 272 is illustrated in FIG. 33 and includes the light sources 281 and 282 and associated photoelectric cells 283 and 284 that are mounted within the frame of each of the reject magazines 68 and 69. When a sufficient number of articles are fed to the reject magazine 69 so that the passage of light from the source 281 to the cell 283 is blocked, the next succeeding article advanced thereto interrupts the beam of light emanating from the source 282. The characteristics of the cells 283 and 284 are analogous to those of other photoelectric cells inasmuch as the resistance thereof is extremely low when a beam of light is directed thereto. When the beam of light to the cells is interrupted, however, the resistance thereof is substantially infinite.

When a beam of light is directed to either or both of the cells 283 and 284, current flows through resistors 571 and 574 which are included in the grid circuits of thyratrons 572 and 576. The voltage developed across resistors 571 and 574 raises the potential at the grid of the thyratrons to a point sufficient to initiate the conduction thereof, thereby resulting in the energization of relays 573 and 426 that are included in the plate circuits of these thyratrons. Accordingly, during operation of the verification machine, the relays 573 and 426 are normally energized. The normally closed contacts 537_a, which are included in the energizing circuits for a plurality of relays 581, are open while the normally open contacts 426_a, which are included in the energizing circuit for the drive motor control relay 416, are closed.

Deenergization of the relay 573 occurs when the beam of light from each of the lamps 281 and 282 is interrupted by the accumulation of rejected combs in the reject magazine 69 and results in the closure of contacts 537_a (FIG. 27). The closure of any one or several of the contacts 537_a completes a path for energizing current to relays 581 in series therewith. When energized, relays 581 draw up contacts 581_a and 581_b. Contacts 581_a complete paths for energizing current to the solenoids 286. Upon being energized, solenoids 286 cause the gates 272 controlled thereby to be raised against the action of the spring 293. The contacts 581_b lock the relays 581 in an energized state and preclude the raised gates 272 from returning to a normal position until a reset button 583, which is included in series with each of the locking circuits, is depressed. When a gate 272 at one of the test stations has been raised, rejected combs will thereafter be fed to the reject magazine 68 and will accumulate therein until the thyratron 576 is rendered non-conductive. When the thyratron 576 is cut off, the relay 426 included in the plate circuit thereof will be deenergized and the associated contacts included in the energizing circuit for the drive motor control relay 416 will be opened to preclude the drive motor from further operation.

The foregoing description is illustrative of but one sequence of exemplary testing operations conducted at stations 61, 62, 63, 66 and 67. Inasmuch as the individual circuits have incorporated therein electrical elements and circuitry which are common to several of these test circuits and because other features thereof are commonly utilized in similar electrical testing networks, the description of the functioning thereof excludes certain operations which obviously result during the performance of tests thereby. For example, the disclosure of details relating to the deenergization of certain relays that results from the opening of a cam operated switch subsequent to the completion of a testing operation has not been included. In view of the above disclosure of a preferred embodiment of the invention, it will be apparent to those skilled in the art that various parts of the apparatus may be varied widely in form without departing from the spirit of the invention. By way of example, the card 71 may be replaced by widely differing forms of automatically detectable data storing devices. In the

illustrated embodiment of the invention, the card 71 carries a single set of data which governs the setting of both the contact testing heads and the fin detecting heads. This is possible because of the relationship of contacts and fins in the finished article being tested. Where such a relationship does not exist, the card may carry separate data for the adjustment of two different testing devices or systems.

Accordingly, it is to be understood that the above-described arrangements are simply illustrative of the application of this invention. Numerous other arrangements may be readily devised by those skilled in the art which will embody the principles of the invention and fall within the spirit and scope thereof.

What is claimed is:

1. A machine for verifying the conformity of the configuration of plastic guide fins and the presence of precious metal contacts on terminals of relay contact combs, which machine comprises a control circuit, drive means, a first means within said control circuit responsive to a coded medium for rendering said drive means operable, a first test means for determining the configuration of plastic guide fins on a relay contact comb, a second test means for ascertaining the presence of precious metal contacts on terminals projecting from the comb, a second means within said control circuit for conditioning said first and second test means for operation in accordance with the coded medium, indexing means actuated by said drive means for advancing a comb into alignment with each of said first and second test means, means associated with each of said first and second test means and said drive means for effecting the operation of said first and second test means subsequent to the alignment of relay contact combs therewith, and discharge means associated with each of said first and second test means and responsive to the ascertainment of a defective comb for rejecting the comb.

2. A machine for automatically verifying the conformity of the configuration of terminals and plastic guide teeth on relay contact combs to predetermined specifications during the indexing thereof through a plurality of test stations, which machine comprises a support frame, a breakdown potential test head mounted within said support frame at a first of the test stations for selectively applying breakdown potential to a comb aligned therewith, a guide tooth verification test head pivotally mounted on said support at a second of the test stations having a plurality of sensing fingers for ascertaining the presence of guide teeth on a comb aligned therewith, a contact metal detector head mounted for pivotal movement on said support frame and situated at a third of the test stations for engaging and sensing the presence of precious metal on the contacts of a comb aligned therewith, drive means, means for initiating operation of said drive means, cam means secured to each of said test heads and co-operable with said drive means for effecting the timed and simultaneous actuation of said test heads, and means for terminating operation of said drive means upon the engagement of a misaligned comb by either said breakdown potential test head, said guide tooth verification test head, or said contact metal detector test head.

3. An automatic article-verification machine for control by a coded medium, which comprises a support frame, drive means mounted within said support frame, a control circuit, means within said control circuit responsive to the coded medium for initiating operation of said drive means, a first test head pivotally mounted on said support frame, a second test head mounted for pivotal movement on said support frame adjacent to said first test head, sensing means secured to each of said test heads, indexing means actuated by said drive means for simultaneously advancing an article into alignment with each of said test heads, linking means secured to said test heads and actuated by said drive means to concomitantly pivot said test heads into engagement with an article aligned there-

with, switch means mounted on each of said test heads and actuated upon the engagement of a misaligned article by one or both of said test heads, means within said control circuit rendered effective upon actuation of said switch means for terminating operation of said drive means, discharge means mounted within said support frame adjacent each of said test heads, and means within said control circuit conditioned for operation in accordance with the coded medium and rendered effective by the operation of said sensing means to actuate said discharge means subsequent to the return of said test heads to an initial position upon the failure of an article being tested to conform to conditions imposed by the coded medium whereby articles failing to conform to said conditions may be discharged.

4. An article-verification machine designed to be controlled by a coded medium which comprises a support frame, drive means mounted within said support frame, a control circuit, means within said control circuit responsive to the coded medium for rendering said drive means operable, a plurality of test heads pivotally mounted in spaced horizontal relationship on said support frame, sensing means secured to each of said test heads, indexing means actuated by said drive means for simultaneously advancing an article into alignment with each of said test heads, linkage means secured to each of said test heads and actuated by said drive means to concomitantly pivot each of said test heads into engagement with an article aligned therewith, switch means mounted on each of said test heads and actuated upon the engagement of a misaligned article by any of said test heads, means within said control circuit rendered effective upon actuation of said switch means for rendering said drive means inoperable, discharge means mounted within said support frame at a position whereat said articles are situated when properly aligned with each of said test heads, and means within said control circuit conditioned for operation in accordance with the coded medium and rendered effective by the operation of said sensing means to actuate said discharge means subsequent to the return of said test heads to an initial position upon the failure of an article being tested to conform to conditions imposed by the coded medium.

5. A machine for verifying the conformity of the configuration of the body portion of an electrical component and the presence of terminals thereof, which machine comprises a control circuit, drive means, a first means within said control circuit responsive to a coded medium for rendering said drive means operable, a first test means for determining the configuration of the body portion of an electrical component, a second test means for ascertaining the presence of terminals of the electrical component, a second means within said control circuit for conditioning said first and second test means for operation in accordance with a coded medium, indexing means actuated by said drive means for advancing an electrical component into alignment with each of said first and second test means, means associated with each of said first and second test means and said drive means for effecting the operation of said first and second test means subsequent to the alignment of an electrical component therewith, and discharge means associated with each of said first and second test means and responsive to the ascertainment of a defective electrical component for rejecting the electrical component.
